UNITED STATES PATENT OFFICE.

JOSEPH EDDY, OF FOSTORIA, OHIO.

WASHING-MACHINE.

1,120,292.

Specification of Letters Patent.

Patented Dec. 8, 1914.

Application filed May 28, 1914. Serial No. 841,612.

To all whom it may concern:

Be it known that I, JOSEPH EDDY, a citizen of the United States, residing at Fostoria, in the county of Seneca and State of Ohio, have invented certain new and useful Improvements in Washing-Machines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to new and useful improvements in washing machines and comprises a simple and efficient apparatus of this nature having various details of construction, combinations and arrangements of parts which will be hereinafter fully described, shown in the accompanying drawings and then specifically defined in the appended claims.

I illustrate my invention in the accompanying drawings, in which:

Figure 1 is a side elevation of the invention with the top thrown open. Fig. 2 is a top plan view. Fig. 3 is a central vertical sectional view through the machine, and 30 Fig. 4 is a top plan view of the false bottom showing bearings in which the same is mounted.

Reference now being had to the details of the drawings by letter, A designates the body of the washing machine which is made preferably of iron and having legs A' of angle iron or other material. Mounted within the body portion of the machine upon the opposite walls are the tubular 40 socket members B fastened one to each wall and each of said members is slotted upon portions adjacent to each other for the reception of the pintles C which project laterally from the false bottom D, which latter has holes D' therein. Springs C' are mounted in each tubular section and upon which said pintles are adapted to rest to give a yielding movement to the false bottom as it is tilted. The opposite ends of the 50 body portion are provided with corrugations or serrations E, forming rubber surfaces.

Bearing members F are mounted upon the top of the machine and a handle H is pro-

vided with laterally extending pintles H' 55 which are journaled in said bearings. Projecting laterally from the shaft are the arms I, each having pivoted to its outer end rods J to the lower ends of which the pounders K are fastened, there being two 60 of said pounders upon either side of the handle, as shown in the top plan view, and which are adapted to press the clothes down against the rubber board.

Mounted within the handle is a stem N, 65 the upper end of which bears against a spring O interposed between said stem and the upper end of the handle and to the lower end of said stem a convexed rubber Q is fastened, the spring O tending to normally hold the latter at its farthest downward throw and yielding against clothes which are interposed between the two rubbers.

At one side of the body portion is a box 75 S for convenience in receiving soap, and to which a wringer may be attached. Underneath the body is a burner T from which leads a pipe T' and forming means whereby the water within the machine may be kept 80 heated.

The operation of my invention will be readily understood. The parts being adjusted as shown and described, the operator by working the handle back and forth 85 may cause the two pounders on either side of the center of the handle to be alternately raised and lowered, pressing the clothes down against the tilting false bottom, thus thoroughly agitating the same and causing 90 the water to circulate back and forth to thoroughly cleanse the clothes.

What I claim to be new is:

1. A washing machine comprising a body portion, a tilting spring-pressed false bottom, a handle pivotally mounted upon the top of the body and having laterally projecting arms, rubbers connected to said arms, and a spring-pressed false bottom having a shank portion extending within 100 said handle.

2. A washing machine comprising a body portion having slotted tubular socket members upon the opposite walls, a tilting false bottom having pintles movable within said 105 slots, springs within the members and upon which the pintles rest, bearing members upon the top of the machine, a hollow han-

dle having pintles journaled within said bearing members, a spring within said handle, a rubber and stem thereon mounted within said handle and bearing against said 5 spring, laterally projecting arms upon said handle, rods pivoted to the arms, and pounds, fastened to the end of each rod.

In testimony whereof I hereunto affix my signature in presence of two witnesses.

JOSEPH EDDY.
